(57) **CLAIM**

The ornamental design for a hand truck, as shown and described.

DESCRIPTION

FIG. 1 is a perspective side elevational view of the hand truck;

FIG. 2 is a similar view showing the nose plate extender in folded-up position;

FIG. 3 is a side elevational view of one side of the hand truck, the opposite side view being identical;

FIG. 4 is a front elevational view thereof;

FIG. 5 is a rear elevational view thereof;

FIG. 6 is a top plan view thereof; and,

FIG. 7 is an under plan view thereof.
